UNITED STATES PATENT OFFICE.

FRANCESCO GRECO, OF TARANTO, ITALY.

REFRACTORY BRICKWORK FOR WATER-TUBE BOILERS.

Application filed April 25, 1919. Serial No. 292,704.

To all whom it may concern:

Be it known that I, FRANCESCO GRECO, a subject of the King of Italy, and residing at Taranto, Italy (whose post-office address is: 5 Via Pisanelli 7, Taranto), have invented certain new and useful Improvements in Refractory Brickwork for Water-Tube Boilers, of which the following is a specification.

The present invention relates to improvements in furnace wall construction, the principal object of the invention being to provide an improved construction whereby the brick work is secured to the metallic frame or casing in such a manner that the 15 use of holding bolts is entirely avoided.

A further object of the invention is to provide a furnace wall construction in which the brick work is insulated from the metallic casing so that the bricks are permitted 20 to freely expand without injury to themselves or to the casing.

With the foregoing and other objects in view, the invention consists in the novel features of construction and combination of 25 parts which will be more fully set forth hereinafter, and particularly pointed out in the claims.

In the drawings accompanying and forming part of this specification,

30 Fig. 1 is an inside end view of a furnace constructed in accordance with the present invention and adapted to accommodate a water tube boiler of the well-known Du Temple type, the brick work being shown 35 only at one side of the furnace;

Fig. 2 is a vertical sectional view taken approximately on the line E—F of Fig. 1, the side wall of the furnace being shown broken away;

40 Fig. 3 is a fragmentary sectional view, taken approximately on the line A—B of Fig. 1;

Fig. 4 is a sectional plan view, taken on the line C—D of Fig. 1; looking in the direction of the arrows, only a portion of the brickwork and the insulation being shown;

Fig. 5 is an outside end view of the furnace;

50 Figs. 6 and 7 are fragmentary views of the side walls of the metal casing of the furnace, illustrating the manner of securing the brick work thereto;

Fig. 8 is a sectional view, taken approximately on the line G—H of Fig. 6;

Fig. 9 is a side view of the means for securing the bricks to the side walls of the metal casing or frame; and

Fig. 10 is a fragment of a sectional view similar to Fig. 4, but on a considerably larger scale.

The same characters of reference designate the same parts in the different figures of the drawings.

Referring to the drawings, 6' designates the end wall of the metallic frame or casing of the furnace, and 6 the side wall. A metal plate 1, preferably of sheet iron, is secured at its upper end to the end wall 6' of the casing and extends downward at an angle therefrom, as shown in Fig. 2. The plate 1 is curved transversely of the furnace, as shown in Figs. 3, 4 and 10, such curvature merging into a straight surface at the upper portion of the plate. The side edges of the plate 1 are formed as shown in Fig. 2, that is to say, they are tapered and curved from the top thereof down to the top of the side walls of the furnace, and are preferably inclined from the top of such side walls toward the bottom thereof. An angle bar 2 conforming in contour to the side edges of the plate 1 is secured to each of said side edges, the purpose of which bar is to retain the bricks against transverse displacement. The brickwork 3 is built up against the inclined curved face of the plate 1, as clearly illustrated in Figs. 2 and 10, the end bricks of each tier being cut out to receive the dovetail formed by the angle iron bars 2. It will thus be seen that the bricks are built up in an inclined position against the solid plate 1, while, as hereinbefore stated, they are held against transverse displacement by the angle bars 2. For permitting the free expansion of the bricks without injury to themselves or to the casing, a layer of insulating material, such as asbestos, designated by the reference numeral 7, is interposed between the plate 1 and the brickwork 3.

For securing the brickwork to the side walls 6 I have provided a plurality of angle irons 8 which are adapted to be arranged vertically of the side walls and spaced apart a suitable distance so as to form an interlocking member between the ends of adjacent bricks, as shown in Fig. 8, the end walls of the bricks being provided with a correspondingly shaped recess 11 to adapt them

to closely fit the angle irons 8. For securing the angle irons to the side walls 6 I have provided a pair of anchor plates 9 for each angle iron, adapted to lie one on each side of 5 the side walls, and a bolt 10 adapted to pass through the plates and the side walls and into the angle irons and be secured thereto by means of a nut, as clearly shown in Figure 9. In order to permit movement of the 10 bolt and the angle iron to correspond with the expansion of the brick, the opening through which such bolt passes through the side walls 6 may be of elliptical formation, as shown at *a*, Fig. 6, although such openings 15 may be circular, but of a diameter larger than that of the bolts. The triangular space formed between the bricks and the angle irons 8 may be filled with insulating material, such as asbestos, as shown at 12 in 20 Fig. 8.

In the end wall 6' of the frame or casing are formed a plurality of openings having shutters 4 which are adapted to open inwardly. The openings are of sufficient size 25 to permit passage therethrough of a workman for the purpose of making repairs. The fact that the doors swing inwardly, as indicated in Fig. 2, causes the shutters or doors to act in the nature of choking shutters, the opening movement of which varies 30 according to the difference in pressure between the outside atmosphere and that within the firebox. This manner of mounting the shutters also serves the purpose of preventing smoke from passing from the combustion chamber to the boiler-room when a fire is being started, because at that time there is no air pressure to force the doors open. Moreover, the opening of the doors 35 inwardly serves to protect the boiler-room from steam in case any of the water tubes become damaged, as the shutters would close under the pressure of the escaping steam. Any suitable locking device may be 40 applied to the shutters to retain them in closed position when desired, as, for instance, when two or more boilers are operating in a single room and there are other boilers in the same room not being operated. By 45 keeping the shutters of the idle boilers closed, the air pressure within the room is not wasted. In the present instance a plurality of air passages 5 are shown passing through the plates 1 and the brickwork 3, 50 such passages serving to create a circulation

of air through the furnace, the air taken into the furnace through these passages having been heated to a certain degree in the space or box formed between the plate 1 and the end wall 6' of the casing or furnace frame. 60 A plurality of small doors 13 may be provided in the side walls of the furnace for permitting the removal of cinders, etc., one of such doors being indicated in Fig. 2.

From the foregoing it will be seen that I 65 have provided a furnace construction in which the use of bolts for securing the brick-work to the frame is entirely eliminated, thereby rendering it unnecessary to provide holes in the bricks for the passage of such 70 bolts, it having been found in practice that such holes are the principal cause of breaking of the brick, and that by reason of this construction the brickwork is maintained in position in a solid and substantial manner, 75 while ample provision is made for the expansion of the brick.

It will be understood, of course, that this 80 construction may be adapted for furnaces using coal as well as those in which a liquid fuel is used.

While I have described in detail the structures herein illustrated, it is to be understood that I do not thereby limit my invention to the precise features of construction 85 shown, as I am aware that many mechanical changes and modifications may be made therein without departing from the spirit and scope of the invention as set forth in the claim appended hereto.

Having thus described my invention, what I claim is:

In furnace construction, the combination 90 of a casing having end walls and side walls, of a curved plate secured within the casing at an angle to one of said end walls, brick-work within said furnace built up parallel to 95 said curved plate and side walls, means carried by the side walls and plate for preventing displacement of the brickwork, and insulating material between the brickwork and said plate and side walls.

In testimony whereof I have hereunto signed my name in the presence of two witnesses.

FRANCESCO GRECO.
